UNITED STATES PATENT OFFICE.

JOSEPH H. SHANK, OF DAYTON, OHIO.

GYMNASIUM BED.

Application filed April 28, 1924. Serial No. 709,409.

To all whom it may concern:

Be it known that I, JOSEPH H. SHANK, a citizen of the United States, residing at Dayton, in the county of Montgomery and State of Ohio, have invented certain new and useful Improvements in Gymnasium Beds, of which the following is a specification.

This invention relates to new and useful improvements in gymnasium beds, and more particularly to a knock-down bed that may be readily set up in a small space such as a room, to support various exercising devices.

It is one of the principal objects of my invention to provide for a small space such as a room in a hotel, dwelling or a like structure, a bed which carries various exercising devices such as stall bars, trapeze rings and a punching bag for the use of adults and children.

It is another object of my invention to provide a gymnasium bed between the head posts and the foot posts of which stall bars may be secured, so that one may obtain the benefit of the exercise they afford while in the bed.

It is another object of my invention to provide a gymnasium bed which supports such exercising means as a chinning bar and a punching bag, for use within the bed by children or outside of it by adults.

It is another object of my invention to mount in two tubular posts of the bed, pulley weights that may be easily removed and changed for those of the desired length and thickness, and which may be easily operated from within the bed or outside of it.

Still another object of my invention is to provide such a gymnasium bed which supports for use over the bed, an adjustable cross bar from which trapeze rings depend.

And still another object of my invention is to provide such a bed which is not only a gymnasium in itself, but which is simple in construction and which may be knocked down and set up with ease.

Other important and incidental objects will be brought out in the following specification, and particularly set forth in the subjoined claims.

In the accompanying drawings illustrating my invention, Figure 1 is a perspective view of my gymnasium bed, showing a number of exercising devices supported thereby. Figure 2 is a longitudinal, section view taken

through the bed. Figure 3 is a longitudinal, sectional view taken through one of the bed posts, showing one of the exercising weights therein. Figure 4 is an elevational view of the end frame at the foot of my gymnasium bed when the latter is knocked down. Figure 5 is a plan view of the top frame of the bed. Figure 6 is a view of one of the side rails therefor. Figure 7 is a detail view of the punching bag. And Figure 8 is a detail view of the chinning bar.

Referring to the accompanying drawings for a detailed description of my invention, the numerals 1, 1 designate two tubular head posts and the numerals 2, 2 designate two tubular foot posts which together form the corner legs of the bed. Tightly fitted on the lower end of each bed post, is a bottom collar 3 and an upper collar 4. Each one of these collars is formed with a tubular boss 5 for a purpose to be hereinafter described. Secured to the bottom of each bed post is a caster 6.

The numerals 7, 7 designate two side rails which may be formed from angle bars, and from each end of which there projects downwardly a pin 8 for entrance into the tubular boss 5 on each one of the upper collars 4 for the purpose of demountably connecting the head and foot posts of the bed together. Projecting downwardly in an inclined manner from the end portion of each side rail 7, is a bracing member 9 which has formed on its end a pin portion 10 for entrance into the tubular boss portion of each one of the bottom collars 3 on the posts. The side rails 7, 7, when connected to the posts as just described, provide a solid bed frame to receive and support a mattress frame and mattress of any suitable type.

The mattress frame illustrated in the drawings comprises side rails 11 and end rails 12 firmly joined together and upon which a spring structure such as the wire netting 13 is secured to support a mattress 14. Secured to the sides of the side rails 11 of the mattress frame are angle pieces 15 which project or hook over the side rails 7, 7 of the bed to removably support the mattress frame upon them.

Firmly secured upon the bed posts 1 and 2 above the collars 4, are collars 16 having inwardly facing tubular projections 17. The collars 16 on the head posts 1, 1 are arranged opposite each other at suitable vertical distances apart, to support stall bars

18 whose ends are fitted into the tubular portions 17 of the collars. The collars 16 on the foot posts 2, 2 are likewise arranged to support a series of stall bars 19. These 5 stall bars are thus arranged so that the occupant of the bed can put his arms on one bar and his feet on an opposite bar to obtain the benefit of the body exercise which they provide.

19 Firmly secured upon the bed posts 1 and 2 just below their tops, are collars 20 to support sleeves 21 that are free to be slipped over the tops of said posts. Projecting inwardly from each sleeve 21, at right 15 angles to each other, are tubular bosses 22 in which are fitted the ends of top side bars 23 and top end bars 24. Free to slide over each top side bar 23 is a collar 25. These two collars 25, 25 support a trapeze bar 26 20 from which there depend two ropes 27, 27, to each one of which there is connected a ring 28. This trapeze bar 26 is longitudinally adjustable to any desired position over the mattress 14 for use by the occupant of 25 the bed.

Freely movable in the upper part of each foot post 2, is an elongated cylindrical weight 29 secured to a cord 30. Journalized in a bearing 31 mounted in the top part of 30 each foot post 2, is a pulley 32 over which its respective cord 30 passes. The upper wall of each foot post is preferably notched to permit its pulley to freely project through it in a direction to allow the cord 30 that 35 passes over the pulley to be brought down over another pulley 33 in a block 34 adjustably secured by a suitable means such as a wire ring 35 to one of the lower stall bars 19. Each cord 30 then passes upwardly to a pulley 36 in a block 37 secured to one hook end of a bar 38, the latter being adjustably secured to a desired stall bar 19 by means of wire rings 39. Secured to the outer ends of the cords 30 40 after they pass over the pulleys 36, are triangles 40 which may be gripped from inside the bed, or outside of it, to draw the weights 29 upwardly in the foot posts 2, 2. (See Figures 1 and 3.) The pulleys 33 and 45 36 are so connected to the stall bars that they may be readily turned to permit the weights to be pulled up and let down from a position within the bed, or outside of it. A child, for instance, may desire to operate 50 the pulley weights from a position within the bed, while an adult may desire to exercise with them from a position near the bed. The fact that the weights are contained within the bed posts, conserves space 55 and permits them to be readily removed, and changed, when desired. While I have shown these weights as being within the foot posts 2, 2, they may be placed within the head posts 1, 1 if desired.

60 65 For the purpose of obtaining a chinning

exercise from inside or outside of the bed, I have provided a substantially flat metal strip 41 having its upper end turned to form a hook 42 which may be applied to one of the top stall bars, with its lower part in engagement with the stall bar beneath, for firm support on either side of said bars. Projecting outwardly from the strip 41 are two tubular portions 43, 43 into which are fitted the ends of a U shaped chinning bar 44. This chinning device may be readily removed to change its position from inside to outside, and vice versa, or from a lower to a higher level, or from a high position to a lower one as when used by a child within the bed.

For the purpose of supporting a punching bag 45 for use from within or without the bed, I employ the following supporting means. The numeral 46 designates a metal strip similar to the strip 41 having an upper hook end 47 for application to a stall bar. Projecting outwardly from the upper, outer part of the strip 46 is a tubular member 48 in which is fitted the inner end of a horizontal rod 49. Secured to the outer end of the rod 49 is a hub 50 to which there is connected a number of downwardly curved radial arms 51 that support at their outer ends a ring 52. These arms and rings form together a frame for the punching bag 45, which is suspended from a cord 53 that is connected at its upper end to the hub portion of said frame.

Formed in the lower part of the metal strip 46 is a hole through which the threaded end of a hook 54 is adapted to project. When the strip is hooked over an upper stall bar, its lower end may be firmly secured to the stall bar below it by the hook 54 which carries on its threaded end a wing nut 55 which will press the lower end of said strip tightly against said lower stall bar. By taking off the wing nut 55 so that the hook 54 may be removed from the lower stall bar, the position of the punching-bag supporting strip 46 may be changed in the same manner that the chinning-bar supporting strip 41 is changed. It is thus possible to so place the punching-bag frame that the bag 45 may be punched from a desired height within the bed or outside of it.

It will now be seen that I have provided a knock-down bed which may be easily set up for use as a gymnasium within a room or other small space. The exercising devices are firmly, compactly and adjustably supported, and many of them may be operated from either within or outside of the bed.

Having described my invention, I claim:

1. A gymnasium bed comprising head and foot corner posts, bottom side rails connecting said posts, stall bars secured between the head corner posts and between the foot corner posts, outwardly projecting body

suspending devices secured to the top stall bars and braced against the lower stall bars, and bracing bars removably connected between the bottom ends of the corner posts and the end portions of the side rails.

2. A gymnasium bed comprising head and foot corner posts, side rails connecting the head and foot posts, a pair of cross bars secured between the corner posts at one end of the bed, a supporting member having a hook end adapted to fit over the top bar, with its lower end braced against the lower bar, and an exercising device secured to said supporting member.

15 3. A gymnasium bed comprising head and

foot corner posts, side rails connecting the head and foot posts, the corner posts at one end of the bed being tubular, a pair of cross bars connected between the tubular posts, a weight vertically movable in the upper 20 end of each tubular post, a cord attached to each weight, a pulley mounted in the upper end of each tubular post, over which its respective cord passes, and pulleys secured to the cross bars to receive said cords to 25 enable them to be pulled from inside the bed frame, or outside of it.

In testimony whereof I have hereunto set my hand this 26th day of April, 1924.

JOSEPH H. SHANK.
